CLAIM

We claim the ornamental design for a truck bed frame assembly,
as shown and described.

DESCRIPTION

FIG. 1 is an isometric view of a truck bed frame assembly;
FIG. 2 is a front elevation view thereof and is a mirror image
of the back elevation view;
FIG. 3 is a left side elevation view thereof and is a mirror
image of the right side elevation view;
FIG. 4 is a top plan view thereof; and,
FIG. 5 is a bottom plan view thereof.
